UNITED STATES PATENT OFFICE.

BENJAMIN WEKLER, OF BROOKLYN, NEW YORK, ASSIGNOR TO THE PEELLE COMPANY,
OF BROOKLYN, NEW YORK, A CORPORATION OF NEW YORK.

VERTICALLY-SLIDING DOOR FOR ELEVATOR-SHAFTS.

1,299,886.

Specification of Letters Patent.

Patented Apr. 8, 1919.

Application filed December 9, 1915. Serial No. 66,006.

To all whom it may concern:

Be it known that I, BENJAMIN WEKLER, a citizen of the United States, and a resident of New York city, borough of Brooklyn, in the county of Kings and State of New York, have invented certain new and useful Improvements in Vertically-Sliding Doors for Elevator-Shafts, of which the following is a specification.

10 This invention relates to improvements in vertically sliding doors for elevator shafts.

The object of my invention is to provide new and improved sliding doors of this type which are made in sections mounted to slide 15 vertically in parallel planes and which are so arranged as to prevent the passage of fire and smoke at the ends and meeting edges of the doors, by means of simple, durable and efficient devices.

20 In the accompanying drawings in which like letters of reference indicate like parts in all the figures:

Figure 1 is a vertical transverse sectional view of my improved doors showing my improvement, the doors being closed.

25 Fig. 2 is an enlarged horizontal sectional view on the line $x-x$ of Fig. 1.

Fig. 3 is an enlarged vertical transverse sectional view of the lower part of the upper 30 door and the lower door, parts being broken out.

Fig. 4 is a horizontal sectional view through the upper door.

Fig. 5 is a plan view of the top of the 35 lower door, parts being broken out.

Fig. 6 is a similar view showing a plate riveted to the upper edge of the lower door.

Fig. 7 is a sectional view on the line $y-y$ 40 of Fig. 6 showing how the suspension chain is connected with the door.

The upper and lower door sections 1 and 2 respectively are mounted to move vertically in parallel vertical planes. The door sections 1 and 2 are suspended from sprocket 45 chains 3 and 4 respectively, which pass over sprocket wheels 5 and 6 respectively, the sprocket wheel 5 being about half the diameter of the sprocket wheel 6, and the sprocket wheels being firmly connected to each other.

50 The sprocket wheels are mounted in a suitable housing and the sprocket chain 4 is connected with a suitable counter-balance weight, and the sprocket chain 3 passes over the sprocket wheel 5 without a counter-weight, as fully set forth in my application

Serial No. 48,593, so that the door sections when the door is opened or closed, have simultaneous vertical movement in the same direction but upon parallel planes, the lower door sections moving approximately twice 60 as fast as the upper door sections.

The door opening 7 is usually provided with a lining formed of a channel bar 8, but it may also be formed of masonry. To the flange 9 of the channel bar 8, at the shaft 65 side of the door opening, or to the wall 10 at the shaft side, an angle bar 11 is bolted or riveted by means of one flange, the other flange of this angle bar projecting into the shaft and being the main guide on which the 70 doors slide. To the inwardly projecting flange of the angle guide bar 11, an angle bar 12 is riveted, the free flange 17 of which is embraced by the U-shaped guide clips 13 which are bolted to a vertical angle bar 14 75 on the T-bar 15 forming the vertical end pieces of the lower door 2. The flange 16 of the angle bar 14 laps over the guide clips and thus also laps over the flange 17 of the angle bar 12 and serves to guide the door as 80 it moves up and down.

In order to prevent flame from passing from the building to the elevator shaft or vice versa, at the side edges of the lower door, when the same is closed, I provide an 85 angle bar 18 which is bolted to that flange 19 of the angle bar 11 which is attached to the wall 10, or to the inner flange 9 of the channel bar 8, and the flange 20 of this angle bar projects toward the door and is adjacent to the inner side of a vertical flange 21 of the T-bar 15 forming the side of the frame of the lower door, so that the flange 20 of the angle bar 18 overlaps the flange 21 90 of the T-bar 15 forming the side of the door 95 frame, and this channel 18 extends from the floor up to the bottom edge of the upper door, when the same is in its lowest position, so that the bottom T-bar 22 of the upper door can rest on the upper edge of the 100 flange 20 of the angle bar 18, when the upper door is in its lowest position. The free edge of the flange 20 of the angle bar 18 extends to the web of the T-bar 15 forming the vertical end member of the lower door, 105 as shown in Fig. 2.

In order to permit the lower door to rise, the flange 23 of the bottom T-bar 24 of the lower door, must be notched as shown at 25 and this notch must be greater than the 110

width of the flange 20, so as to allow for expansion in case of fire.

As the doors lap when closed and the upper edge of the lower door extends up 5 higher than the lower edge of the upper door, and as the lower edge of the upper door rests on the top of the baffle flange 20, the upper edge of this flange must be offset, that is to say, part of it must extend up- 10 ward beyond the lower edge of the upper door, so as to form a wing 26, which extends to the underside of the top T-bar 27 of the lower door. The top T-bar 27 of the lower door 2 is provided with a notch 28 at each 15 end of the door, into which a link of the suspending chain 4 for the lower door, is inserted, in the conventional manner and to confine said link in said notch the outer edge of the notch must be closed. This is 20 accomplished by bolting a plate 29 to the top of this T-bar 27 in such a manner that it laps over the edge of the T-bar 27 and extends toward the surface of the upper door 1. This plate or bar 29 has the inner cor- 25 ners cut out, as shown at 30, so as to form a lug or wing 31 which extends across the notch 28 and confines the chain within said notch and prevents withdrawing it.

In the overlapping part of the plate 29, I 30 provide a series of slots 32 which extend longitudinally of the plate. To the under- side of the bottom T-bar 22 of the upper door, an angle iron 34 is riveted in such manner that its flange 35 extends upward 35 between the doors 1 and 2. To the said up- wardly extending flange, plates 36 are riveted, which terminate at their upper ends in upwardly projecting pins 38. When the doors are closed and both are in their lower- 40 most positions, the pins 38 pass through the slots 32 in the plate 29 and thus lock the doors together at their meeting edges and prevent their being separated laterally. Furthermore the plate 29 acts as a baffle 45 plate and prevents flame and smoke from the loft from passing up between the doors into the shaft.

When the doors rise, the lower door moves about twice as fast as the upper door, 50 and when the doors are opened, the plate 29 moves upward faster than the angle iron 34 and thus the pins 38 are disengaged from the slots 32.

As the lower door is moved up and down- 55 ward, it slides parallel with the flange 20 of the angle iron 18, which is close to the flange 21 of the vertical T-bar 15 of the door frame and overlaps the same and the free edge of the flange 20 of the angle bar 60 18 is close to the web of the T-bar 15, thus precluding the passage of flame through the door opening, into the elevator shaft as the flange 20 of the angle bar 18 acts as a baffle for flame and smoke.

65 Having described my invention what I

claim as new and desire to secure by Letters Patent is:

1. The combination with a door comprising an upper and a lower section, both movable vertically in the same direction but in 70 parallel planes at a door opening, of vertical guides at opposite sides of the door opening, guide members carried by said door sections respectively coöperating with said guides, and plates projecting from the wall 75 adjacent each side of said opening, into close proximity to the side frames of said lower section, said plate being of a height to be engaged by the upper section when the door is closed, whereby when the door is 80 closed, the gaps between the lower section and below the upper section, and the wall adjacent the door opening will be substantially closed.

2. The combination with a door comprising an upper and a lower section, both movable simultaneously in the same direction but in parallel vertical planes at a door opening, said lower section having an angular, overhanging frame, of vertical guides 90 at opposite sides of the door opening, guide members carried by said door sections respectively coöperating with said guides, and plates projecting from the wall adjacent each side of said opening within the over- 95 hanging frame of the lower door section, said plates being of a height to be engaged by the upper section when the door is closed, said frame being slotted or notched to span the edge of said plate, whereby when the 100 door is closed, the gaps between the lower section and below the upper section, and the wall adjacent the door opening will be substantially closed.

3. The combination with a door comprising an upper and a lower section, both movable vertically in the same direction but in parallel planes at a door opening, of vertical guides at opposite sides of the door opening, guide members carried by said door sections respectively coöperating with said guides, and plates projecting from the wall adjacent each side of said opening, each of said plates being notched in its upper end to form a recess adapted to receive the lower 115 edge of the upper door section when the door is closed whereby said doors overlap and the gaps between the lower section and below the upper section, and the wall adjacent the door opening will be substantially 120 closed.

4. The combination with a door comprising an upper and a lower section movable vertically in the same direction but in parallel planes at a door opening, of plates projecting from the wall adjacent each side of said opening within the frame of the lower door section and into close proximity to the surface of the said section, said frame being slotted, or notched to span said plate 125 130

and being of a height to be engaged by the upper section when the door is closed and a plate projecting from the top frame of the lower section within the frame of the upper section and in close proximity to the surface of said upper section whereby when the door is closed all gaps between the lower section, and the wall adjacent said opening and between the door sections, will be substantially closed.

5. The combination with a door comprising an upper and a lower section movable vertically in the same direction but in parallel planes at a door opening, of plates projecting from the wall adjacent each side of said opening within the frame of the lower door section and into close proximity to the surface of said section, said frame being slotted or notched to span said plate and 10 being of a height to be engaged by the upper section when the door is closed, a plate projecting from the top frame of the lower section within the frame of the upper section and in close proximity to the surface 15 of said upper section whereby when the door is closed all gaps between the lower section, and the wall adjacent said opening and between the door sections, will be substantially

closed, and means forming an interlock between the door sections when they are closed 30 whereby the formation of a gap between said plate carried by said lower section and the surface of the upper section by stresses on either of said sections, is prevented.

6. The combination with a door comprising an upper and a lower section movable vertically in the same direction but in parallel planes at a door opening, of vertical guides at opposite sides of the door opening, guide members carried by said door sections 40 respectively coöperating with said guides, a guide member carried by each of said sections and a flange member carried by said door sections respectively adjacent said guide members, the flange of said member 45 occupying a plane parallel with said guides respectively, the edges of said flange and said guides overlapping each other.

Signed at New York city, borough of Manhattan, in the county of New York and 50 State of New York, this 8th day of December, A. D. 1915.

BENJAMIN WEXLER.
